UNITED STATES PATENT OFFICE.

FRANCIS M. FRANKLIN AND JAMES G. RYERSEE, OF JEFFERSON, IOWA.

HAME-COUPING.

SPECIFICATION forming part of Letters Patent No. 366,161, dated July 5, 1887.

Application filed April 28, 1887. Serial No. 236,451. (No model.)

To all whom it may concern:

Be it known that we, FRANCIS M. FRANKLIN and JAMES G. RYERSEE, citizens of the United States of America, residing at Jefferson, in the county of Greene and State of Iowa, have invented certain new and useful Improvements in Hame-Couplings; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Our invention relates to certain new and useful improvements in means for attaching traces or tugs to hames, the object of our invention being to provide a cheap, simple, and effective means whereby the tugs can be attached to their hames and a large bearing be provided for the coupling, so that there will be but little wear upon the parts.

Our invention consists in the construction and combination of the parts, as will be hereinafter fully set forth, and specifically pointed out in the claims.

In the accompanying drawings, which illustrate our invention, Figure 1 is a perspective view of our improved hame coupling, and Fig. 20 2 is a longitudinal sectional view.

A refers to the portion of our improved coupling which is attached to the hame in the ordinary manner—that is to say, by passing the ends *a a* through perforations in the hame until they reach the offsets or larger portions *a'*, the ends *a''* being upset or riveted over washers or a suitably-perforated plate on the opposite side of the hame. The portion A is provided centrally with an elliptical portion, 35 *A'*, recesses *b*, being formed between this elliptical portion and the shanks B. The portion connecting the shanks B, and upon which the elliptical portion *A'* is formed, is curved slightly inwardly, as shown at *B'*, and these shanks B are curved from this connecting portion, as shown, thus providing a construction whereby the elliptical portion will be at an angle with the shanks, so that the draft will be received directly upon the front 50 end of the elliptical portion, as shown.

C refers to the portion which is secured to the tug or end of the trace by suitable rivets, which pass through the members *c c*; and these members diverge slightly from each other, and are connected by a semi-spherical socket, D, 55 within which the portion A' will bear. The portion A can be readily inserted or attached to the portion C by moving the same slightly rearwardly and turning the same at nearly right angles with the socket; and when the 60 parts are attached to the hame and tug they cannot be separated from each other.

In a hame-coupling constructed as shown the tug will be permitted to have a slight rotary movement, as well as a slight vertical 65 movement, upon the portion attached to the hame, so that the tug will accommodate itself to the line of draft, and twisting of the trace will be obviated; and as a large bearing is provided for the parts there will be but little 70 wear.

We are aware that prior to our invention it has been proposed to provide hame-couplings with large parts at such points where the wear will come, and we do not claim such construction as our invention; but 75

What we claim as new, and desire to secure by Letters Patent, is—

1. In a hame-coupling, the portion A, having a semi-spherical or elliptical portion, A', 80 between the members or shanks B, and a socket adapted to fit over said portion and provided with members *c c* for attaching the same to the tug, substantially as shown, and for the purpose set forth.

2. The combination of the portion A, provided with curved shanks B and a connecting portion upon which is formed a semi-spherical projecting portion, A', which extends inwardly at an angle with said shanks, 90 and a portion, C, having a socket, D, and members *c c*, to which the tug is attached, substantially as shown, and for the purpose set forth.

In testimony whereof we affix our signatures in presence of two witnesses.

FRANCIS M. FRANKLIN.
JAMES G. RYERSEE.
